Thomas N. McNish, INVENTOR

Frank P. McEnton,
his ATTORNEY.

UNITED STATES PATENT OFFICE.

THOMAS NORRIS MCNISH, OF KEARNEY, NEW JERSEY.

OIL-CAN.

1,288,090.

Specification of Letters Patent. Patented Dec. 17, 1918.

Application filed July 20, 1918. Serial No. 245,943.

To all whom it may concern:

Be it known that I, THOMAS NORRIS MCNISH, a citizen of the United States, residing at Kearney, in the county of Hudson and State of New Jersey, have invented 5 certain new and useful Improvements in Oil-Cans, of which the following is a specification, reference being had therein to the accompanying drawings, which form a part 10 thereof.

My invention relates to oil cans, and more particularly to a type thereof having a valve controlled spout which, when the can is not in use, will prevent the flow of oil from the 15 can.

Heretofore various types of so called non-leakable oil cans of the type above referred to, have been devised, the common characteristic of such cans being the use of a spring 20 bottom in the body of the can bearing upon a valve stem controlling the flow of oil through the spout, the valve mechanisms, which are of various types, being so constructed that the valve will be opened with 25 the initial displacement of a spring bottom, and can be closed only when this bottom has completely returned to its normal condition.

In an oil can made in accordance with my invention, I employ a simple valve mechanism carried by, and forming a part of, the spout. Said mechanism is so constructed and arranged in relation to the bottom of the can body as to relieve said bottom from the stresses of the valve spring during the 35 initial displacement or flexures of said bottom, in a manner to increase the facility with which said bottom may be displaced when ejecting oil from the can. The tension of this valve spring is utilized to impart the 40 desired reflex action to the bottom, the relation of parts being such as to cause the valve to be seated before said bottom returns fully to normal. This construction insures the 45 desired tight seating of the valve under all conditions, and avoids likelihood of distortion of the bottom of the body of the can resulting in a sufficient displacement of the valve to permit the escape of oil. Furthermore, if desired, a spring bottom may be 50 entirely dispensed with, the valve spring being relied upon to both seat the valve and to restore the bottom of the can body to normal.

The invention consists primarily in an oil can embodying therein a can body having an opening therethrough, a flexible bottom therefor extending substantially at right angles to the axis of said opening, a spout, means detachably connecting said spout with said can body, a closure plate carried by the bottom of said spout and having a port therein through which said spout communicates with said can body, a valve 55 adapted to control said port, a valve stem carried by said valve and projecting within said can body, the end of said valve stem being spaced away from said flexible bottom, and a spring acting upon said valve stem to normally seat said valve; and in such other 60 novel features of construction and combination of parts as are hereinafter set forth and described, and more particularly pointed out in the claims hereto appended.

Referring to the drawings, Figure 1 is a view, partly in section and partly in elevation, of an oil can embodying my invention; and

Fig. 2 is a side elevation of the lower part of the spout and the valve mechanism carried thereby.

Like letters refer to like parts in both of said views.

In the embodiment of the invention shown in the accompanying drawings, I have indicated at *a* an ordinary can body having a flexible bottom *b*, and a boss *c* having an opening therethrough, said bottom extending substantially at right angles to the axis of said opening. While in the drawings I have shown a conventional form of oil can body, this body may take any desired form, so long as the relation of the parts above referred to, is maintained. The spout *d* is permanently secured to a plug *e*, which closes the opening in the boss *c* and permits 85 said spout *d* to be detachably connected to the can body, as by means of the screw threads shown, which is the usual way of connecting a spout to the body of an oil can.

Permanently secured to the bottom of the plug *e* is a closure plate *f* having a port *f'* therein through which the spout *d* may communicate with the interior of the can body. This port is normally closed by a valve *g* formed of leather, rubber, composition, or other suitable material, the diameter of this

- valve being sufficient to completely close the port f' . The valve g is mounted upon a valve stem h consisting of an ordinary rivet, the head h' of which engages the valve g .
- 5 Said stem h projects, when the can is assembled, within the can body a , terminating adjacent the bottom b , but spaced away therefrom sufficiently to leave enough clearance between said stem and said can body, to permit a substantial flexure of said bottom before it engages said stem.

10 Encircling the stem h is a coiled spring i , which is normally held in tension by the washer j carried by the stem h and secured in position by the upsetting of the end of said stem. The spring i is of sufficient strength to insure the seating of the valve g under all conditions, and to overcome the elasticity of the bottom b in the event that 15 a spring bottom is employed, although, if desired, the bottom b may be made of flexible material having no inherent elasticity.

15 The operation of the herein described oil can is substantially as follows:

20 When it is desired to fill the can, the plug e is removed by unscrewing it from the boss c in the usual manner, the valve g and its appurtenances passing freely through the opening in said boss, so as to leave an unobstructed opening through which the can body may be readily filled. When the can is filled, the plug is reinserted in the boss, positioning the parts as shown in Fig. 1, so 25 that the valve g will close the port f' and prevent the escape of the oil, irrespective of the position of the can.

25 When it is desired to eject oil, the bottom b is pressed in the usual manner, the initial displacement of said bottom, sufficient to develop pressure within the can, occurring before the bottom engages with the stem h , thus causing said bottom, during this initial displacement, to be relieved from the pressure of the spring i , and permitting the can 30 to be used under conditions practically identical with the ordinary can. The movement of the bottom b , subsequent to this initial movement, will impart movement to the stem h against the tension of the spring i , sufficient to open the port f' and permit the oil to flow freely through the spout d . Immediately, the pressure upon the bottom b ceases, the spring i , through the stem h , will 35 impart a return movement to said bottom, irrespective of any elasticity inherent thereto, the valve g being seated by said spring i before the bottom b returns to its normal position.

40 In addition to facilitating the ease with which the can may be actuated to eject oil, the positioning of the stem h away from the bottom b , avoids necessity for any nicety in the adjustment of said stem in relation to said bottom, and insures the positive seat-

ing of the valve, irrespective of the bottom 45 taking a set, as a result of frequent use, closer to the boss c than contemplated in the original design of the can.

I have found in practice that oil may be ejected upwardly by first filling the spout 70 and permitting the valve to close while the spout is thus filled and then actuating the bottom of the can in the usual manner.

If it be found, after the can has been used, that a small quantity of oil remains 75 in the spout, said spout may be drained by holding the can upright and actuating the bottom b to open the valve g .

A can made in accordance with my invention is particularly adapted for handling 80 gasoline, or other light oils used as a priming charge for internal combustion engines, as I have found in practice that the valve is sufficiently tight to prevent the escape of such lighter oils.

85 A can made in accordance with my invention may be readily stored in a drawer or a tool box, where it is necessary to lay the can upon its side, particularly as the impact of light articles with the bottom b will 90 have no tendency to open the valve g , and a light weight may rest upon said bottom b without having any tendency to actuate the valve stem h in a manner to open the valve.

95 It is not my intention to limit the invention to the precise details of construction shown in the accompanying drawings, it being apparent that such may be varied without departing from the spirit and scope of the invention.

100 Having described the invention, what I claim is new and desire to have protected by Letters Patent, is:—

1. An oil can embodying therein a can body having an opening therethrough, a 105 flexible bottom therefor extending substantially at right angles to the axis of said opening, a spout, means detachably connecting said spout with said can body, a closure plate carried by said spout and having a 110 port therein through which said spout communicates with said can body, a valve adapted to control said port, a valve stem carried by said valve and projecting within said can body to a point adjacent, but spaced 115 away from, said flexible bottom, and a spring acting upon said valve stem to normally seat said valve.

2. An oil can embodying therein a can body having an opening therethrough, a 120 flexible bottom therefor extending substantially at right angles to the axis of said opening, a spout, means detachably connecting said spout with said can body, a closure plate carried by said spout, and having a 125 port therein through which said spout communicates with said can body, a headed rivet passing through said port and project-

ing within said can body to a point adjacent, but spaced away from, said flexible bottom, a valve below the head of said rivet and adapted to control said port, a washer secured to said rivet adjacent the lower end thereof, and a coiled spring seated between said closure plate and said washer.

Copies of this patent may be obtained for five cents each, by addressing the "Commissioner of Patents, Washington, D. C."

In witness whereof I have hereunto affixed my signature this 18th day of July, in the presence of two subscribing witnesses. 10

THOMAS NORRIS McNISH.
